UNITED STATES PATENT OFFICE

GEORGE R. BINDER, OF RIVERSIDE, ILLINOIS

RADIO FREQUENCY TRANSFORMER

Application filed April 29, 1929. Serial No. 358,802.

The present invention is directed to a radio frequency transformer circuit, or more particularly to a radio frequency transformer used in a radio frequency circuit.

One of the objects of the present invention is to provide a novel and improved radio frequency transformer which will give the maximum selectivity commensurate with reasonable voltage amplification.

A further object of the invention is to provide a novel and improved radio frequency transformer in which the secondary coil is in the closest possible inductive relation with respect to the primary coil.

A still further object of the invention is to provide a novel and improved radio frequency transformer which has a minimum number of turns or coils of wire in the secondary, so as to reduce the resistance in the secondary, thereby increasing the selectivity.

These and other objects are accomplished by providing a construction and an arrangement of the various parts in the manner hereinafter described and particularly pointed out in the appended claims.

Referring to the drawings, Fig. 1 is a schematic drawing of a simple regenerative thermionic vacuum tube circuit such as is well known in the art.

Fig. 2 is a schematic drawing representing the arrangement of the primary and secondary of the transformer to which the invention applies, and

Fig. 3 is a side elevational view of the coil showing the mechanical arrangement of the primary and secondary of the transformer.

The present invention is directed to a radio frequency transformer in which the maximum selectivity is attained by making the coupling as close as possible and the number of turns as low as possible.

It is well known in the art that resistance in the secondary circuit mitigates against the selectivity of this circuit. In this invention, coupling between the coils is made very close which means that the energy transfer from primary to secondary is very high. This high ratio of energy transfer from primary to secondary is attained in the ordinary radio frequency transformer by having a large

number of secondary turns placed in inductive relation to the transformer's primary. This large number of turns induces undesirable resistance into the secondary, thereby impairing the selectivity, although the desired high ratio of energy transfer is secured. The present invention secures the same high ratio of energy transfer by placing the turns of the secondary in closer inductive relation to the turns of the primary so that the same degree of energy transfer may be attained by the use of fewer turns in the secondary. The elimination of these additional turns in the secondary, of course, reduces the resistance as is well known, in the secondary circuit, thereby giving a maximum selectivity consistent with the given energy transfer.

In Fig. 2, the fifty turns represented by reference character A is the tickler coil in the ordinary regenerative vacuum tube circuit. The first ten turns of the primary indicated by the reference character C is wound clockwise. All the turns on the coil wound in a clockwise direction and indicated by reference character B, represent the secondary of the radio frequency transformer. All the other turns wound in a counter-clockwise direction and indicated by the reference character C and connected up with the first ten turns C' represent the primary of the radio frequency transformer. As shown in Fig. 1, the primary or first ten turns indicated at C' is placed in series with the antenna and ground, as indicated at D. The secondary of the radio frequency transformer is connected in the grid circuit as indicated at E, and shunted by a variable condenser, as shown at F, as is common in the practice.

The manner in which the coil is wound is as follows: The primary and secondary are preferably wound on a paper tube as indicated at G, Fig. 3 in which ten turns of the primary are first wound in a clockwise direction on one end of the tube, at this point a tap being brought out and ten turns of the same primary are wound in a counter-clockwise direction adjacent the ten turns previously wound. Wound adjacent the last ten turns are wound sixteen turns of the

secondary in a clockwise direction. Wound adjacent the last sixteen turns is a single turn or a continuation of the previous primary turns. Wound adjacent the previous single turn are fourteen turns which are a continuation of the secondary turns wound in a clockwise direction. Wound adjacent the previous fourteen turns is a single turn of the primary which is a continuation of the previous primary turns. Wound adjacent the single turn are four turns of the secondary which are a continuation of the previous turns of the secondary. Wound adjacent the four turns are three turns of the primary wound in a counter-clockwise direction. The end of this last three turns terminates as is indicated at H. Wound adjacent the previous last three turns are another three turns of the primary wound in a counter-clockwise direction, the beginning of which remains unconnected as shown at H'. Wound adjacent the previous three turns are sixteen turns of the secondary which are a continuation of the previous winds of the secondary and are wound in a clockwise direction. Wound adjacent the previous sixteen turns is a single turn of the primary which is a continuation of the previous three turns of the primary and is wound counter-clockwise. Wound adjacent the last previous one turn are eight turns of the secondary which is a continuation of the last previous sixteen turns of the secondary. Wound adjacent the last previous eight turns is a single turn of the primary which is a continuation of the last previous turn of the primary. Wound adjacent the last single turn are eight turns of the secondary which are a continuation of the previous eight turns of the secondary. Wound adjacent the last previous eight turns are ten turns of the primary which are a continuation of the last previous single turn of the primary. This last ten turns are connected with the ground. It will be noted that by having the primary C broken as shown at H and H' and having the aerial and ground connected in series with the first ten turns of the primary C' that the selectivity of the transformer is increased to a maximum.

What I claim as my invention and desire to secure by Letters Patent is:

1. A radio frequency transformer having its primary and secondary interwoven on substantially a single cylindrical surface with certain coils running in a clockwise direction and certain others in a counter-clockwise direction.
2. A radio frequency transformer comprising a cylindrical core having a major portion of its primary wound in a counter-clockwise direction and its secondary wound in a clockwise direction and interwoven with the primary, whereby a maximum close coupling is attained, thereby increasing the selectivity of the same.

3. In a radio frequency transformer comprising a cylindrical core having the major portion of its primary and secondary coils interwoven on substantially a single cylindrical surface and wound in opposite directions so as to increase the selectivity of the same to a maximum.

4. A radio frequency transformer having a primary and secondary coil interwoven, the primary being broken circuited whereby the maximum selectivity is attained.

In testimony whereof I have signed my name to this specification, on this 11th day of April, A. D. 1929.

GEORGE R. BINDER.
